ELLIS DOTY, OF JANESVILLE, WISCONSIN, ASSIGNOR FOR ONE-HALF HIS
RIGHT TO THOR JUDD.

Letters Patent No. 102,784, dated May, 10 1870.

IMPROVEMENT IN GAS-GENERATORS.

The Schedule referred to in these Letters Patent and making part of the same.

To all whom it may concern:

Be it known that I, ELLIS DOTY, of Janesville, in the county of Rock and State of Wisconsin, have invented a new and useful Improvement in Gas-Generators; and I do hereby declare the following to be a full, clear, and exact description of the same, reference being had to the accompanying drawings, in which—

Figure 1 is a perspective view of my apparatus.

Figure 2 is a vertical longitudinal sectional elevation of the same.

Figure 3 is a vertical transverse section through the reservoir and feed-wheel.

Figure 4 is a perspective view of my meter-wheel in operative position, immersed in water, a portion of the shell being broken away.

This invention relates to apparatus for carbureting atmospheric air for the purpose of producing an illuminating-gas; and

It consists—

First, in the arrangement of devices to form an automatic feed.

Second, in the evaporating surface, formed of a single thickness of cloth, suspended so that the surplus oil may drip to the surface of the water.

Third, in taking the supply from or below the level of the floor.

Fourth, in the arrangement of pipe and cock to replenish the water in the meter-case, and withdraw any surplus water, or the oil collected upon the surface of the same.

Fifth, in the manner of constructing a seat for the cone-valve.

Sixth, in the manner of mounting the generator upon its supporting-frame, so that it may be partially rotated upon its axis.

I am aware that gas-generators have been constructed having an automatic feed-apparatus to supply fresh oil as fast as required.

I am also aware that a current of air has been produced by the revolution of a meter-wheel partially submerged in water, but I am not aware that the arrangements of devices referred to above, and hereinafter claimed, have been employed in gas-generators.

That others may understand the construction, operation, and purposes of my invention, I will particularly describe it.

The generator A is a metallic cylinder, supported in a suitable frame composed of the legs B and brackets C, which latter fit the cylindrical surface of the generator A, and receive and support its weight.

The legs B are bound together by the brace and tie-rods D D.

Upon the top or upper surface of the cylinder A, the gas-holder E and the reservoir and feeding-apparatus case F are located.

Within the cylinder A there is a meter or fan-wheel, G, by means of which a current of air is forced to move through the apparatus, and secure the generation of gas as rapidly as may be desired.

A supplemental frame, H, supports a shaft, I, upon which is wound the cord J, and, by means of the weight K, or its equivalent motor, the driving-pulley L is actuated, and from thence, by means of a belt, M, motion is transmitted to the meter-wheel shaft N, and to the other operative machinery of the apparatus.

By means of the ratchet and pawl O P, and the balanced crank Q, the weight K may be wound up at any time, and the motive power renewed.

Having now indicated the general arrangement and construction of my apparatus, I will particularly describe the various details as I have preferred to construct and arrange them.

The meter-wheel shaft N has its bearings in boxes, R S, attached to, and protruding from, the ends of the cylinder A.

These boxes pass through orifices in the frame-legs B for the purpose of securing steadiness in the apparatus, but it is not intended that any considerable portion of the weight of the apparatus shall be supported by the bearing of said boxes R S in the legs B B.

One of the boxes R is capped at its end, so that the end of the shaft does not protrude.

At the opposite end of the shaft N there is a pulley, T, upon which the belt M runs to drive the meter-wheel.

The meter-wheel G is a cylinder, having a fan at each end, the vanes U U of which are connected by the spiral partitions P, so that, as said wheel is rotated, a current of air is introduced at one end and expelled at the other, said partitions being soldered along the edge to the shell G.

Extending from one end to the other of the cylinder A are the bridge-wires or rods V V, located a little distance from the inner surface of said cylinder.

These wires are four or five in number, and are not disposed around the lower part of the cylinder, as they are only required to support the cloth or felt sheet W, which constitutes evaporation-surface.

The air-pipe Y projects downward through the bottom of the cylinder A, and has its lower end near or

below the surface of the floor upon which the apparatus stands, and its upper end in close proximity to the induction end of the meter-wheel G, and within a chamber formed by the false cylinder-head H', as shown in fig. 2.

It is not necessarily arranged in the precise manner shown in the drawing, fig. 2.

When the meter-wheel is set in motion, atmospheric air is drawn through the pipe Y, and caused to pass through the meter-wheel G.

Motion is thus imparted to it, and it is impelled, after leaving the meter-wheel, to flow back along the walls of the cylinder, and in contact with the evaporating surface of the cloth W, and finally into the gas-holder, where it is secured and retained for consumption.

The air-pipe Y extends downward to a point close to or below the floor for this purpose.

Carbureted air is heavier than pure atmospheric air, and, therefore, when it escapes from a gas-holder or generator, it falls to the floor and settles in the lowest portions of the same, gradually filling the apartment, until it finds an outlet through which it may flow to still lower levels. Hence, many accidents have occurred when a lighted candle or lamp has been placed upon the floor at a considerable distance from a vessel containing hydrocarbon oils.

When the air-pipe Y is brought close to the floor, it is apparent that, if there is any free carbureted air thereon, it will be drawn up into the machine, and thus all dangerous accumulation of such vapor in the apartment will be impossible.

When in use, the cylinder A is partially filled with water, say to, or a little above, the line x x. This insures the desired action of the meter-wheel in producing a current of atmospheric air, as above-described, and it also prevents any accumulation of carbon oil or refuse of any kind at the bottom of the generator.

A draw-off cock, a, is provided, to discharge the contents of the cylinder A, and a surface-cock, b, is provided to discharge any accumulation of oil which may have collected upon the surface of the water.

The whole apparatus may be partially rotated upon its bearings, to bring the cock b to the surface of the water, when the same happens to be slightly above or below said cock b.

A gauge, c, indicates to the eye the water-lever within the generator, and the feed-pipe d, which descends below the water-surface enables the attendant to replenish the water-supply at any time when it may be necessary.

The reservoir e, for the carbon oil which may be employed, is located within the case F, above the cylinder A.

The reservoir e is provided with a glass gauge, f, by means of which the quantity of oil within the reservoir may be ascertained, and at its top there is an orifice, g, through which it may be replenished at any time.

At the bottom of said reservoir is a depression, h, into which dips the periphery of the feed-wheel i, which is mounted upon a horizontal shaft j, and driven from the shaft N by means of the cone-pulleys k l, and the belt m.

The feed may thus be regulated by increasing or diminishing the speed of the wheel i.

A number of pockets, n n, are made in the edge of the wheel i, to take up, at each revolution, definite quantities of the carbon oil, and the edge of said wheel is also grooved, as shown, to facilitate the discharge of the contents of said pockets, in the manner following.

As the pocket reaches the highest point in the revolution of the wheel i, its contents begin to run out in the direction of the wheel's motion. The edge

of said wheel being grooved, the liquid follows said groove, and is caught upon the edge of the scraper p, the end of which is made to fit in the before-mentioned groove.

By the scraper p, the carbon liquid is conducted to the chamber q, and from thence it flows along the pipe r to the cup s, and from thence it flows into the generator and upon the surface of the cloth W, over which it distributes itself.

By the means above described, it will be readily perceived that the quantities of gasoline or other carbon oils to be introduced into the generator may be regulated and adjusted as desired, and the quantity introduced may be regulated so as to exactly balance the quantity volatilized and absorbed by the air at each revolution of the meter-wheel.

It will also be perceived that no gas can escape from the generator into or through the reservoir, because the chamber t between the reservoir and the generator is made gas-tight, and the mouth of the feed-pipe r dips below the constant surface of the carbon oil in the cup s, said surface being constantly at the level of the upper mouth of the short tube u.

The gas-holder E does not differ in principle from the ordinary gas-holders.

It consists of a tank to receive and hold water, and gauge-pipe, r, to regulate the height of the inclosed water.

Rising from the generator, and opening above the level of the water, is a stand-pipe, w, through which gas flows from the generator to the interior of the bell x, which may be weighted as required.

An outlet-pipe, A', takes the gas from the interior of the bell at the level of the upper end of the stand-pipe, and, bending downward, leaves the holder at its lower portion, as shown in fig. 1.

At its lowest point, a small pipe, B', is inserted to convey to the interior of the generator either water or the product of condensation which may accumulate in the gas-pipe.

A valve, C', is attached in such a way that the mouth of the stand-pipe w will be closed when the holder has been filled with gas to its utmost capacity, and said valve I find it convenient to arrange as follows:

The valve is made in the form of a cone, suspended by a wire or cord from the dome of the bell x.

The apex of the valve is upward, and it hangs within the stand-pipe w, so that, as the bell x ascends, the valve will ascend also, and, a suitable seat being placed at the mouth of the stand-pipe, the same will be closed when the bell is filled with gas.

A good and efficient seat may be constructed with a sheet of India rubber, D', having a circular perforation, and confined between two plates of metal, as shown in fig. 2.

Having described my invention,

What I claim as new is—

1. The feed-wheel i, provided with the buckets n and scraper p, in connection with the chamber q, pipe r, cup s, and pipe u, arranged substantially as and for the purpose set forth.

2. In a gas-generator, the evaporation-cloth W, supported upon rods V, substantially as and for the purpose set forth.

3. In combination with a gas-generator, the air-supply pipe Y, arranged to take air from the floor or below, as and for the purpose set forth.

4. In combination in a gas-generator, wherein is employed hydrocarbon oil and atmospheric air, a single case, A, partially filled with water, a meter-wheel, G, partially submerged in the same, an evaporating-surface permanently located above the meter-wheel and water, and an automatic feeding device, all arranged substantially as set forth.

5. In a gas-generator to be partially filled with wa-

ter, as set forth, a feed-pipe, *d*, protruding below the surface of the same, for the purpose specified.

6. In a gas-generator partially filled with water, and provided with an evaporator-cloth, *W*, as described, a surface-cock, *b*, for the purpose specified.

7. In combination with the holder *x*, stand-pipe *w*, and valve *C*, a valve-seat, *D*, constructed with a sheet of rubber confined between metallic plates, as set forth.

8. The arrangement of the gas-generating cylinder *A*, and the supporting-frame *B*, provided with lugs *C*, or their equivalents, so that said cylinder may be partially rotated upon its axis, as and for the purpose set forth.

ELLIS DOTY.
